COMBUSTION TURBINE

Sanford E. Richeson, Brooklyn, N. Y.

Application December 6, 1945, Serial No. 633,217

9 Claims. (Cl. 60—41)

1

My invention relates to combustion turbines and has particular reference to turbines operated by hot gaseous products of combustion, the turbine operating a compressor for supplying air to a combustion chamber.

My invention has for its object to provide a combustion turbine of the general character indicated above in which the compressor is so constructed as to reduce frictional losses to a point at which they will practically disappear.

Another object of my invention is to provide specially constructed blades which will withstand a relatively high temperature thereby making it possible to maintain high operating temperatures in the turbine for increasing its power output and efficiency. The use of high temperatures makes it also possible to eliminate the use of intercoolers in the compressor, thereby also reducing losses and increasing efficiency.

The foregoing and other objects and features and advantages of my invention are more fully explained in the accompanying specification and drawing in which:

Fig. 1 is a sectional elevational view of my turbine;

Fig. 2 is a detail sectional view of the blades;

Fig. 3 is a sectional view of the same taken on the line 3—3 of Fig. 1;

Fig. 4 is a sectional detail view of the rotary compressor.

My combustion turbine comprises a tubular casing or stator 1 having gradually increasing diameters from the rear or intake end (at the left in Fig. 1) to the front or exhaust end (at the right in Fig. 1), being of a frusto-conical shape. The casing is provided with the rear and front end plates 2 and 3 respectively with bearings 4, 5 for a central shaft 6. The end plates are supported on floor brackets 9, (Fig. 3). The stator is provided with several rows of turbine blades 14. Between the stationary blades 14 are located rotary blades 15 mounted on a tubular rotor 16, also of a frusto-conical shape. The rotor is closed at the ends by end plates 17, 18 mounted on the shaft 6 and sealing the space 19 in the rotor.

Hot burning gases are supplied to the turbine blades from a combustor 22 supported on a bracket 23 attached to the rear plate 2 and having an exhaust pipe 24 connected with an annular heater 25 in communication with the intake opening of the turbine. Fuel, liquid or gaseous, is supplied to the combustor by a nozzle 26 which may be provided with a conventional throttle valve operated by a conventional governor. Compressed air is delivered to the combustor by a pipe

27 extending from an annular casing 28 of a centrifugal compressor. The compressor is designed to compress outside air and heated precompressed vapors from the rotor chamber 19. For compressing the outside air, large vanes 30 are provided extending from the outside of the front end plates 18 of the rotor and enclosed by an inner portion 31 of the casing 28. Vapors from the rotor chamber 19 are exhausted through ducts 32 connected with a disc-shaped hollow impeller 33 having a narrow annular nozzle 34 opening into an annular Venturi restriction 35 opening into the casing 28. The impeller is provided with curved blades 36 as shown more clearly in Fig. 4, and stationary blades 37 are provided in the Venturi 34, curved in the opposite direction, the blades of the impeller act as turbine blades for adding a rotary movement to the shaft 6.

The stator is cooled by vapors of a liquid, preferably mercury which allows for a considerably higher operating temperature, the boiling point of mercury being 674° F. Mercury for this purpose is delivered by a pump 40 operated by the shaft 6 and gears 41, 42, through a pipe 43 connected to a heating coil 45 supported in an exhaust housing 44. Mercury is vaporized in the coil and is delivered in the form of vapor by a pipe 46 into a cooling jacket 48 surrounding the stator. The vapors pass through the jacket, being guided by spirally arranged baffles 49 which cause the vapors to make several revolutions around the stator before they emerge through a pipe 50. The outer shell of the stator is made of steel or other alloy which is not affected by mercury such as an alloy of lead, sodium, copper and iron. The blades 14 made of heat resisting alloy, and to facilitate the conduction of heat from the blades, a layer of a good heat conducting metal 51 is provided, such as silver, with silver plugs 52 on the blades 14 (Fig. 2).

The pipe 50 is connected to a nozzle 55 through which the mercury vapors are directed into the hollow shaft 6 through a Venturi restriction 56 for increasing their velocity and forming a seal 45 for the vapors in the rotor. The velocity is further increased by causing the vapors to pass through radial tubes 57 extending to the rotor blades 15 which are made hollow inside to facilitate their cooling by the vapors. The rotor is also 50 lined inside with a mercury resisting metal or alloy, with a lining 58 of silver or other heat conducting material between the inner lining and the refractory metal of the blades (Fig. 2). The opening of the nozzle 55 is controlled by an inner 55 nozzle 60 movably supported in the rear of the

outer nozzle 55 and moved by a screw 61 controlled by a suitable conventional pressure responsive device 62 for maintaining a desired pressure at the nozzle. The inner nozzle 60 is connected by a pipe 64 with the pump 40 and delivers liquid mercury or other liquid into the nozzle 55. A thermocouple 63 is placed in the nozzle 55 and is connected with a thermostat control valve 59 in the pipe 64 for regulating the temperature to regulate the flow of mercury. The liquid breaks up into droplets and boosts pressure and provides a frictionless seal, delivering a mixture of mercury vapors and liquid mercury into the hollow shaft 6 from which the mixture is projected by centrifugal force against the inner wall of the rotor and the hollow spaces in the blades.

Presence of mercury vapors in the cooling medium makes it possible to maintain the turbine on a high efficiency level by raising the operating temperatures of the blades. Thus, the mercury, vaporized in the coil 45 by the exhaust heat, is delivered at 700-800° F. into the spiral jacket 48 around the stator, cooling the stationary blades. The heated vapors are then injected into the hollow shaft 6 together with the mercury droplets, which are vaporized, reducing the temperature of the mixture to about 1000° F. A certain amount of the outside air is admitted through a clearance between a disc 65 on the nozzle 55 and a movable disc 66 slidably supported on the shaft 6 and operated by a centrifugal governor 67 which closes the clearance between the discs 65 and 66 when the shaft is not rotating, thereby preventing loss of the vapors when the turbine is not operating. The amount of the air admitted through this clearance during rotation of the shaft can be regulated for maintaining a desired temperature of the vapors in the nozzle 55.

The vapors are ejected at a high speed from the radial pipes propelled by the centrifugal force of the rotor which may make as much as 7000 R. P. M. Liquid mercury is evaporated by the heat of the blades, and the superheated vapors pass through the ducts 32 and are discharged at high velocity through the annular nozzle 34 into the collector 28 from which they are forced into pipes 70 connected with an annular condenser 71 surrounding the stator. The condenser is provided with a plurality of pockets 72 for the condensed mercury arranged at different points of the periphery so that the mercury can be collected in any position of the turbine as, for instance, when it is used on an airplane. The pockets are connected by pipes 73 with the intake of the pump 40. Valves 74 are provided in the pipes 73 operated by magnets 75 for closing the valves when there is no mercury in the pocket.

The mercury will be readily condensed since its temperature will be reduced to about 500° F. by the air admitted through the large blades 30 and heated by the compression in the second stage, i. e., Venturi 35. The air, separated from the mercury, leaves the condenser 71 by pipes 76 connected with a heating coil 77 supported in the annular exhaust chamber 44 and are finally delivered by the pipe 27 into the combustor as was explained above.

The gases from the combustor pass into the turbine at a temperature of 1800-2000° F. or as high a temperature as the cooled blades and parts will stand. The ability to operate at such temperatures depends upon the materials alone, but by cooling the parts subjected to such tempera-

tures, higher operating temperature can be reached even with the same materials as are now in use, and thus greatly increasing the overall efficiency.

Condensing temperature can be regulated by louvres 80 in an air jacket 81 around the turbine, the louvres being operated by a thermostatic control device 82 of a conventional type. The jacket 81 has a common inner annular wall 83.

If water is used instead of mercury, then the condenser must be kept below 212° F. If desired, steam can be admitted into the combustion chamber, increasing the overall efficiency, but a constant supply of water must be then available. Such a system can be used to advantage on locomotives, for instance.

The use of mercury in my system has an important advantage in that it eliminates the use of a cooling system for the compressed air, and greatly increases the efficiency of the turbine, which depends on the temperature of the air before expansion in the combustor. The elimination of the cooling system reduces the weight of the power plant thus rendering it practical for aircraft.

The exhaust gases emerging through exhaust pipes 85 can be directed to the rear of the aircraft, adding to the propelling power on the rocket principle.

Because of the large mass of the mercury vapors, their passage through tubes 57 increases the pressure virtually without friction or loss of power in any substantial degree. The pressure is still further increased by the centrifugal compressor-nozzle 34, whose peripheral speed will be very great because of its large radius.

As an added means to prevent the loss of vapors, a closing disc 86 is provided at the front sliding on an extension 87 of the shaft 6 and held normally in a closing position against a flange 88 on the housing 31 by a spring 89 on the shaft 87 acting on centrifugal weights 90. The disc 86 opens the intake for the blades 30 when the shaft 6 is rotating.

With such an arrangement it is possible to introduce liquid fuel into hollow rotor and to compress combustible vapors in the chamber 28 delivering these vapors directly to the combustor 22.

A starting motor 91 is provided for the rotor operated from a battery (not shown) which will be charged by the motor when it is operated as a generator during rotation of the turbine shaft.

The shaft 87 can be connected by suitable gears 92, 93 with a shaft 94 of a propeller (not shown) or other mechanism.

It should be noted that the intermediate lining 58 between the shield metal and the refractory metal 14, 15 can be so selected as to take up the difference in expansion between the shield metal and the refractory metal.

It will be understood that various features and principles of each of the embodiments of the invention above described or referred to may be utilized or substituted in the other embodiments.

While the invention has been described in detail with respect to certain particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor, the shaft being hollow at one end; tubular ducts extending radially from the shaft to the rotor blades; means to admit air and a cooling liquid into the space in the rotor through the hollow portion of the shaft; a compressor for the combustion chamber operatively connected to the shaft; means to admit heated vapors with the air from the rotor into the compressor; means to admit heated vapors with the air from the rotor into the compressor; means to separate the air from the vapors; and means to deliver the air into the combustion chamber.

2. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor, the shaft being hollow at one end; tubular ducts extending radially from the shaft to the rotor blades, the rotor blades having cavities opening into the space in the rotor; the ducts being adapted to admit air into the rotor through the hollow portion of the shaft; a compressor for the combustion chamber operatively connected with the shaft; means to admit heated vapors from the rotor into the compressors; and means to admit fresh air into the compressor for cooling and condensing the vapors; means to separate the heated air from the condensed vapors; and means to deliver the heated air into the combustion chamber.

3. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor, the shaft being hollow at one end; tubular ducts extending radially from the shaft to the rotor blades, the rotor blades having cavities opening into the space in the rotor; the ducts being adapted to admit air into the rotor through the hollow portion of the shaft; a compressor for the combustion chamber operatively connected with the shaft; means to admit heated vapors from the rotor into the compressor; means to admit fresh air into the compressor for cooling and condensing the vapors; means to separate the heated air from the condensed vapors; means to heat the

separated air by the exhaust gases; and means to deliver the heated air into the combustion chamber.

4. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor, the rotor blades having cavities opening into the space in the rotor; the ducts being adapted to admit air into the rotor through the hollow portion of the shaft; a compressor for the combustion chamber operatively connected with the shaft; means to admit heated vapors from the rotor into the compressor; means to admit fresh air into the compressor for cooling and condensing the vapors; means to control the temperature of the condenser; means to separate the hot air in the condenser from the condensed liquid; and means to deliver the separated hot air into the combustion chamber.

5. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor, the shaft being hollow at one end; tubular ducts extending radially from the shaft to the rotor blades; a Venturi restriction at one end of the shaft; a nozzle extending into the Venturi restriction; means to deliver a liquid through the nozzle and Venturi restriction into the hollow shaft; and means to admit outside air into the Venturi restriction.

6. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in communication with the intake opening and comprising a combustion chamber; means to admit a cooling medium into the rotor; the shaft being hollow at one end; tubular ducts extending radially from the shaft to the rotor blades; a Venturi restriction at one end of the shaft; a nozzle extending into the Venturi restriction; means to deliver a liquid through the nozzle and Venturi restriction into the hollow shaft; means to admit outside air into the Venturi restriction; and means responsive to the pressure in the nozzle to regulate the position of the nozzle in the Venturi restriction.

7. In a combustion turbine the combination of a tubular housing; a plurality of rows of spaced stationary blades in the housing; a rear and a front end plate closing the ends of the housing; a shaft rotatively supported in the end plates;

a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor; the shaft being hollow at one end; tubular ducts extending radially from the shaft to the rotor blades; a Venturi restriction at one end of the shaft; a nozzle extending into the Venturi restriction; means to deliver a liquid through the nozzle and Venturi restriction into the hollow shaft; means to admit outside air into the Venturi restriction; turbine blades in the Venturi restriction; and curved blades in the nozzle, the blades being curved in a direction for producing reaction forces, augmenting the rotary torque of the rotor.

8. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor, the shaft being hollow at one end; tubular ducts extending radially from the shaft to the rotor blades; means to admit a vaporizable liquid into the rotor through the shaft and through the ducts thereby obtaining vapors at a high pres-

sure; a centrifugal compressor operated by the shaft; and means to admit the vapors into the compressor.

9. In a combustion turbine the combination of a tubular housing; a plurality of rows of spaced stationary blades in the housing; a rear and a front end plate closing the ends of the housing; a shaft rotatively supported in the end plates; a tubular rotor mounted on the shaft in the housing; a plurality of rows of blades on the rotor; the rear end plate having an intake opening and the front end plate having an exhaust opening; a vessel in a communication with the intake opening and comprising a combustion chamber; means to admit a cooling medium into the rotor, the shaft being hollow at one end; tubular ducts extending radially from the shaft to the rotor blades; means to admit a vaporizable liquid fuel into the rotor and thereby obtaining vapors at a high pressure; a centrifugal compressor operated by the shaft; and means to admit the vapors into the combustion chamber.
